SLICING MACHINE

Filed Sept. 6, 1928

UNITED STATES PATENT OFFICE

CORNELIS F. M. VAN BERKEL, OF WASSENAAR, NETHERLANDS, ASSIGNOR TO U. S. SLICING MACHINE COMPANY, OF LA PORTE, INDIANA, A CORPORATION OF INDIANA

SLICING MACHINE

Application filed September 6, 1928, Serial No. 304,234, and in Great Britain September 26, 1927.

This invention relates to machines for slicing meat and other substances.

Slicing machines have previously been proposed in the operation of which the substance to be sliced is mounted on a rotary table and is carried thereby recurrently past a slicing knife rotating about a stationary axis. The flywheel effect of the rotary table renders the machine particularly easy to operate. 10 Moreover, the rotary table may, if desired, be so constructed that several different pieces of substance can be clamped thereon. Slicing machines have also been proposed in which the substance-carrying table is arranged to oscillate through a comparatively small angle, such machines being particularly convenient where a small piece of substance has to be quickly cut into slices. 15

The object of this invention is to provide 20 a machine possessing the advantages of both of the above kinds of machines.

In accordance with the invention, the slicing machine comprises a table which is capable of being either rotated or oscillated, as 25 desired, past the slicing knife of the machine.

A carrier may be pivotally mounted on the stationary frame of the machine, and the table may be rotatably mounted on the carrier, means being provided for rotating the 30 table while the carrier is maintained stationary, or for oscillating the carrier while the table is fixed thereon.

In order that the invention may be clearly 35 understood, one embodiment thereof, chosen by way of example, will now be described with reference to the accompanying drawing, whereon:

Fig. 1 is a view of a slicing machine constructed in accordance with the invention, the machine being shown partly in elevation and partly in section;

Fig. 2 is a plan of the machine, with parts thereof broken away;

Fig. 3 is a fragmentary elevation, the view being in the direction of the arrow III in Fig. 2.

The stationary frame of the slicing machine shown in the drawing comprises a base 50 1 and an upright bracket 2 mounted thereon.

A rotary knife 3 is journaled in the bracket 2 and has a driving connection with a hand-rotatable flywheel 4 journaled in the base 1. The said driving connection comprises a flywheel-shaft 5, a counter-shaft 6, 55 intermeshing bevel gear wheels 7, 8 and 9, the gear wheels 7 and 9, respectively, being secured to the shafts 5 and 6 and the gear wheel 8 being secured to a shaft 10, and a chain drive 11 between the counter-shaft 6 and the knife shaft 12. The shaft 10 extends vertically upwards through the base 1 and acts as a pivot to a carrier 13, which is borne by wheels 14 riding on the base 1. A material 60 supporting member in the form of a circular 65 table 15 is centred on a pivot-pin 16 upstanding from the carrier 13.

The table 15 would be provided with known 70 means for clamping on it several different pieces of substance to be sliced by the knife 3. In the construction shown, four independent clamping means would be provided and would be associated with automatic mechanism, forming no part of the present 75 invention, for feeding all or any of the pieces of substance intermittently towards the knife in the working of the machine. It is to be understood that simply one clamping means, or other number thereof, might be provided. The clamping means are indicated conventionally in the drawing by the chain dotted lines 17.

The table 15 has an internally toothed rim 15' into or out of mesh with which a pinion 18 can be moved. The pinion 18 is slidably mounted on the shaft 10, but is not rotatable relatively thereto, and can be shifted into or out of mesh with a spur wheel 19 secured to the upper end of a short crankshaft 20 journaled in, and passing through, the carrier 13. 90 The crankshaft 20, at its lower end, has a crank 21 and crankpin 22, which latter is pinned to one end of a connecting rod 23 anchored at its other end to a pin 24 on the base 1.

It will be apparent that, if the pinion 18 were rotated, (as it will be whenever the flywheel 4 is rotated) while in mesh with the toothed rim 15', the table 15 would rotate, but, if the pinion 18 were rotated while in 100

mesh with the spurwheel 19, the carrier 13 would be oscillated about the shaft 10, by the crank 21 and rod 23.

A hand lever 25 is provided for controlling the pinion 18. The hand lever 25 is fulcrumed, at 26, on the carrier 13 and has a projection 27 which enters a groove 28 in the boss of the pinion. When the handle 29 of the hand lever 25 occupies its lower position (in which it is shown in the drawing) the pinion 18 is raised into mesh with the toothed rim 15' and the handle is positioned between the arms of the locking member 30. With the hand lever 25 so positioned, the carrier 13 would be effectively locked to the base 1 by the locking member 30, so that, if the flywheel 4 were rotated, the table 15 would rotate continuously about a stationary axis, viz. the axis of the pivot-pin 16. On the other hand, when the handle 29 is raised, the hand lever 25 will engage in a notch 31 in the rim 15' (see Fig. 3), while the pinion 18 will mesh with the spurwheel 19. The carrier 13 will not now be locked to the base 1, but will be locked instead to the table 15, so that, if the flywheel 4 were rotated, the carrier 13 and the table 15 would oscillate in unison about the axis of the shaft 10.

Four notches 31, displaced at angles of ninety degrees from one another, would be formed in the rim 15', so that any selected clamping means 17 could be brought into operative relationship with the knife 3 by adjusting the table 15 on the carrier 13.

Other changes in details of construction will readily occur to those skilled in the art and may be made without departing from the scope of the invention.

Having thus described an embodiment of my invention, what I desire to secure by Letters Patent of the United States is:—

1. In a slicing machine having a slicing knife, the combination with a material support, means for rotating said support to move material thereon past the edge of said knife, and means for oscillating said support to move material thereon past the cutting edge of said knife.

2. A slicing machine comprising in combination a slicing knife, a pivotally mounted carrier, a material support rotatably mounted on said carrier, means for holding said carrier stationary, means for locking said carrier and support together, and driving means for rotating said support and reciprocating said carrier.

3. A slicing machine comprising in combination a slicing knife, a pivotally mounted carrier, a material support rotatably mounted on said carrier, said support having a plurality of spaced material holding means thereon, driving means for rotating said support and reciprocating said carrier, means for locking said carrier stationary, and means for locking said carrier to said support

in selected positions so as to reciprocate the material on any desired one of said material holding means past the edge of said knife.

4. A slicing machine comprising in combination a slicing knife, a pivotally mounted carrier, a material support rotatably mounted on said carrier, means for holding said carrier stationary, means for locking said carrier and support together, driving mechanism, and means for selectively engaging said driving mechanism with said carrier and support to rotate said support and reciprocate said carrier.

5. A slicing machine comprising in combination a base member, a slicing knife, a pivotally mounted carrier, a table rotatably mounted on said carrier, driving mechanism, a member movable to selectively engage said driving mechanism with said carrier and table to rotate said table and to reciprocate said carrier, means co-operating with said member for holding said carrier stationary when said driving mechanism rotates said table, and means co-operating with said member for locking said table and carrier together when said driving mechanism reciprocates said carrier.

6. A slicing machine comprising in combination a base member, a slicing knife, a carrier pivotally mounted on said base member, a table rotatably mounted on said carrier, driving mechanism, a lever pivotally mounted on said carrier and formed at one end to selectively engage said driving mechanism with said carrier and table to rotate said table and to reciprocate said carrier, means on said base member for engaging said lever, and means on said table for engaging said lever.

7. A slicing machine comprising in combination a slicing knife, a pivotally mounted carrier, a table rotatably mounted on said carrier, means for holding said carrier stationary, means for locking said carrier and table together, driving mechanism, means associated with said table to cause rotation thereof when engaged by said driving mechanism, a shaft journaled on said carrier, a crank on said shaft, a connecting rod one end of which is carried by said crank and the other end of which is pivoted, and means on said shaft for engaging said driving mechanism to rotate said shaft.

8. A slicing machine comprising in combination a slicing knife, a rotatably mounted material support, reciprocatory mechanism, driving mechanism, means for connecting said driving mechanism with said material support to cause rotation thereof, means for connecting said driving mechanism with said reciprocatory mechanism, and means for detachably connecting said reciprocatory mechanism with said material support.

9. A slicing machine comprising in combination a slicing knife, a base, a shaft journaled in said base, a driving gear and a shift-

able gear on said shaft, a pivotally mounted carrier, a rotatable table on said carrier, gear means associated with said table, a gear having a crank and connecting rod, means for reciprocating said carrier, means for shifting said slideable gear into meshing relation with said gear having said crank and connecting rod means and with said gear means associated with said table, and means for detachably connecting said carrier to said table.

10. A slicing machine comprising in combination a slicing knife, a base, a shaft journaled in said base, a driving gear and a shiftable gear on said shaft, a pivotally mounted carrier, a rotatable table on said carrier, gear means associated with said table, a pinion having a crank and connecting rod means for reciprocating said carrier, a member for shifting said slideable gear into meshing relation with said pinion and with said gear means associated with said table, and means on said table co-operating with said member to lock said table and carrier together when said slideable gear is moved into meshing relation with said pinion.

11. A slicing machine comprising in combination a slicing knife, a base, an upright shaft journaled in said base, a driving gear on the lower end of said shaft, a gear slidably mounted on the upper end of said shaft, a pivotally mounted carrier, a rotatable table on said carrier, gear means associated with said table, a gear having a crank and connecting rod connection with said base and carrier, means for shifting said slideable gear into meshing relation with said gear having said crank and connecting rod connection and with said gear means associated with said table, and means for detachably connecting said carrier to said table.

12. A slicing machine comprising in combination a slicing knife, a base, an upright shaft journaled in said base, a driving gear on the lower end of said shaft, a gear slidably mounted on the upper end of said shaft, a pivotally mounted carrier, a rotatable table on said carrier, gear means associated with said table, a gear having a crank and connecting rod connection with said base and carrier, a lever pivoted on said carrier for selectively shifting said slideable gear into meshing relation with said gear having said crank and connecting rod connection and with said gear means associated with said table, means on said table co-operating with said lever to lock said table and carrier together when said slideable gear is in mesh with said gear having said crank and connecting rod connection, and means on said base co-operating with said lever to lock said carrier to said base when said slideable gear is in mesh with said gear means associated with said table.

13. A slicing machine comprising in combination a slicing knife, a base, an upright

shaft journaled in said base, a driving gear on the lower end of said shaft, a gear slidably mounted on the upper end of said shaft, a carrier pivoted about the axis of said shaft, a table rotatably mounted on said carrier at a point spaced from said shaft, a ring gear on said table, a pinion on said carrier having a crank and connecting rod connection with said base, means for shifting said slideable gear into meshing relation with said ring gear and into meshing relation with said pinion, means for holding said carrier stationary, and means for locking said carrier and table together.

14. A slicing machine comprising in combination a slicing knife, a rotatably mounted material support having a plurality of spaced material holding means thereon, reciprocating mechanism, driving mechanism, means for connecting said driving mechanism with said material support to cause rotation thereof, means for connecting said driving mechanism with said reciprocating mechanism, and means for detachably locking said reciprocating mechanism and material support together in selected positions of said support to reciprocate the material on any desired one of said material holding means past the edge of said knife.

15. A slicing machine comprising a slicing knife, an oscillatable support, a table pivoted on said support, means for oscillating said support, and means for moving said table about its pivot.

16. A slicing machine comprising a slicing knife, a pivoted support, a carriage pivoted on said support and angularly adjustable thereon, and a single means for selectively moving said support about its pivot and adjusting the angular position of said carriage on said support.

17. A slicing machine comprising a slicing knife, a base, an upright shaft journaled in said base, a driving gear on the lower end of said shaft, a gear slidably mounted on the upper end of said shaft, a carrier pivoted about the axis of said shaft, a table rotatably mounted on said carrier at a point spaced from said shaft, an internal gear mounted on said table, a pinion on said carrier operatively connected by means of a crank and a connecting rod to said base, means for shifting said slideable gear selectively into engagement with said internal gear and said pinion, means for holding said carrier stationary with respect to said base, and means for locking said carrier and table together.

In testimony whereof I have signed my name to this specification on this 17th day of August A. D. 1928.

CORNELIS F. M. VAN BERKEL.
